UNITED STATES PATENT OFFICE.

ISAAC ANDERSON, OF SAGINAW, MICHIGAN, ASSIGNOR OF ONE-HALF TO
THOMAS A. PERROTT, OF SAME PLACE.

PIPE-WRENCH.

SPECIFICATION forming part of Letters Patent No. 340,410, dated April 20, 1886.

Application filed August 3, 1885. Serial No. 173 429. (No model.)

To all whom it may concern:

Be it known that I, ISAAC ANDERSON, a citizen of the United States, residing at Saginaw, in the county of Saginaw and State of Michigan, have invented certain new and useful Improvements in Pipe-Wrenches; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention, and is a side view, the handle being broken off. Fig. 2 is a vertical section, the handle being only partially in section. Fig. 3 is a detail view in perspective. Fig. 4 is a detail view in perspective. Fig. 5 is also a detail view in perspective.

This invention has relation to pipe-wrenches; and it consists in the construction and novel arrangement of devices, all as hereinafter set forth, and pointed out in the appended claim.

In the accompanying drawings, the letter A designates the handle of the wrench, having a reversed cam-shaped arm, B, made concave in its bearing portion C. The back of this arm is provided with a notch or bearing, D, to engage the transverse stop-pin E of the jaw-head F, which is pivoted to the handle at the junction of the arm B. This jaw-head F consists of the lateral parallel portions G G, 35 which are connected by the pin E, and by the pivots H and I, the latter connecting the outer ends of said lateral portions. The general form of the head is concave from the handle,

as indicated at K, the concave bearing being formed, mainly, by the longer forward arms, L, 40 of the portions G. To the outer or forward ends of said arms is connected, by the pivot I, the curved jaw N, having the concave bearing m, toothed on its inner face, and provided with a guard-arm, P, which plays between the lateral portions of the jaw-head.

In applying the wrench the curved jaw N is placed on the pipe and turned toward the handle, so that its back will engage the cam-arm of said handle, the pipe thus being 50 grasped between said curved jaw and the concave bearing K of the jaw-head. By turning the handle in such a manner as to force the cam-arm upon the back of the curved jaw N a firm purchase will be obtained on the 55 pipe, whether it be of large or small diameter. By moving the handle in the opposite direction the wrench can be easily detached.

Having described this invention, what I claim, and desire to secure by Letters Patent, 60 is—

The handle having the cam-arm provided with the concave bearing C and the notch bearing D, the pivoted jaw head composed of the two parallel parts G G and having the 65 stop, and the curved biting-jaw having the serrated bearing, and the guard-arm pivoted to the forward end of the said jaw-head, all combined to form a wrench, substantially as specified.

In testimony whereof I affix my signature in presence of two witnesses.

ISAAC ANDERSON.
